CARL F. LUNDEBERG, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,121,642.

Specification of Letters Patent. Patented Dec. 22, 1914.

Application filed August 12, 1910. Serial No. 576,798.

To all whom it may concern:

Be it known that I, CARL F. LUNDEBERG, a citizen of the United States, residing in Hartford, in the county of Hartford and State of Connecticut, have invented certain new and useful Improvements in Type-Writing Machines, of which the following is a specification.

This invention relates to means for enabling the platen to be released from the control of the usual line-space wheel.

In carrying out the invention, the usual line-space wheel is provided with a drum; and an arm within said drum but connected to the platen has a frictional bearing upon the interior periphery of the drum. This bearing is in such a place, and the arm is so pivoted, that an arc described by the arm about its pivot would be very nearly parallel with the internal periphery of the drum. A spring tends to turn the arm about its pivot, to force it into wedging engagement with said internal periphery of the drum. When attempt is made to rotate the line-space wheel in the same direction as the spring is pressing (or to rotate the platen in the opposite direction), the arm is caused to bind even more firmly against the drum, so that it becomes impossible to effect relative movement of the line-space wheel and drum in this direction. A companion arm is provided, operating in a similar manner to prevent relative movement of the line-space wheel and drum in the opposite direction. Thus any relative movement of the platen and line-space wheel is prevented. These arms are preferably mounted upon the same pivot, and are preferably made long enough to extend clear across the drum, so as to exert a suitable wedging action upon the interior of the drum. Provision is made for forcing the arms to release the drum at will.

In the accompanying drawings, Figure 1 is a perspective, showing the invention applied to an Underwood writing machine. Fig. 2 is a detail perspective of the releasing head and cover plate of the clutch mechanism. Fig. 3 is a sectional view of the platen releasing mechanism in normal position. Fig. 4 is a rear view of the detent and

its releasing lever. Fig. 5 is an end view, showing the detent and the clutch mechanism in use. Fig. 6 shows the detent and the clutch members released. Fig. 7 is a sectional view, showing the clutch releasing mechanism in operative position.

The usual cylindrical platen 1 is mounted rigidly upon an axle 2 journaled in the ends 3 of a platen frame. An annular line-space wheel 4, having a friction drum portion 5, is mounted loosely upon a disk 6, the latter secured by a hub 6^a to the axle 2. The disk has an annular flange 7 affording a bearing upon which the wheel and drum may turn. The edge 6^b of the disk fits in a recess in the line-space wheel, to prevent axial displacement of the latter, which is confined between said disk and a cover plate 26. The line-space wheel 4 is operated by a lever 9 through a slide 10 and pawl 11, and is engaged by the usual detent arm 8, which carries a roll 31 to seat in any of the notches in the wheel, the arm 8 being pressed by a spring 32.

A pair of clutching arms 12, 12 is pivoted at 13, to the disk or head 6, and extend from side to side of the drum 5 on opposite sides of the axle 2, and are within the general contour of the flange 7, the latter being cut away to give room for the arms to play. The arms may carry shoes 14 to bear forcibly against the inner periphery of the drum to connect the line-space wheel and platen. The arms 12 are so pivoted that their free ends would describe an arc nearly coincident with the curvature of the interior periphery of the drum, against which said arms (or the shoes thereon) are pressed by a spring 15 which forces the arms in opposite directions to bite or grip the interior periphery of the drum, so that rotation of the line-space wheel and platen in either direction will cause either one or the other of the arms to bind even more tightly against the drum. The pivot of each lever, for this purpose, is placed nearly in a line passing through the axis of the platen and through the central point of contact of the lever (or the shoe thereon) with the inner periphery of the drum 5, as will be understood from Fig. 5, wherein A indicates the line above

mentioned, and B the line passing through the pivot and contact point of one lever. It will be understood that one arm 12 is pressed by the spring toward the right, and the direction of its swing is such that the rotation of the line-space wheel to the right relatively to the platen would tend to turn the arm in the same direction and make it bind more firmly against the drum or wheel. Therefore relative movement of the platen and line-space wheel in this direction is prevented. The other arm is similarly pressed toward the left, and should the wheel be turned in the same direction, its frictional contact with the arm would act to tighten the grip between the arm and wheel, so that relative rotation of the line-space wheel and platen in this direction is also prevented.

The single bearing surface of the drum serves both to support it revolvably upon the flange 7, and also to receive the pressure of the shoes 14. Moreover, owing to the large diameter of said flange 7, the pressure of the shoes upon the drum, which draws the latter forcibly against said flange (on the opposite side thereof from said shoes) aids in holding the line space wheel against independent rotation. Furthermore the levers are compactly arranged within the flange 7.

The outer ends of the arms 12 may be rounded to form knuckles 25 loosely fitting or pivoting in sockets in the shoes, whereby the latter adjust themselves to the contour of the drum.

By pressing inwardly a button or finger piece 16, which is rigidly connected with a plate 19 by rods 18, the latter passing loosely through the hand wheel 17, said plate is forced against a releasing head 20. Said head 20 carries a pair of cams in the shape of pointed teeth 21, to engage the outer edges of the respective clutch arms 12 and crowd or wedge said arms toward each other, to release the shoes 14 from forcible contact with the drum, and thereby disconnect the platen from the line-space wheel, (Figs. 6 and 7). The head 20 is preferably guided and prevented from binding on the axle, by a pair of shoulder screws 20^a projecting from the flange 7 and passing loosely through the head, and by a hollow boss 23 sliding on the hub 6^a of the disk 6. Said arms 12 may be chamfered at their outer edges, as at 22, to form bearing surfaces engaged by the beveled ends of the cams 21. A spring 24 returns the head 20 to normal position, (Fig. 3) withdrawing the teeth 21 from the arms 12, whereupon the spring 15 forces the arms apart to force the shoes 14 against the drum 5.

The aforementioned cover plate 26 may be interposed between the drum 5 and the head 20 to protect the clutch mechanism in addition to holding the line-space wheel in place,

such plate preferably being secured to the flange 7 by the shouldered guides 20^a and having orifices 27 through which the cams 21 pass.

The spring-pressed detent roll 31 may be cast off from the line-space wheel by a releasing lever 28, pivoted intermediate its ends at 29 to the detent arm 8. The free end of lever 28 bears against the drum, as the lever is swung by its opposite end from idle position (Fig. 5) to active position (Fig. 6), thereby jacking the detent away from the line-space wheel. The end of the lever 28 has a shoe or concavity 30 which fits around the curved surface of the drum.

Having thus described my invention, I claim:

1. In a typewriting machine, the combination with a line-space wheel having a drum, and a platen rotatable relatively thereto, of a friction clutch mechanism to connect the platen and line-space wheel including a pair of wedging arms having a common pivot eccentric to the axis of the line-space wheel to frictionally engage the drum to lock the platen and line-space wheel together, and releasing means to shift said arms out of contact with the drum.

2. In a typewriting machine, the combination with a line-space wheel having a drum, and a platen rotatable relatively thereto, of a clutch mechanism to releasably connect the platen and line-space wheel, including a pair of pivotally supported wedging arms connected with the platen and having a common pivot, shoes having bearings upon the rounded free ends of the arms to enable the shoes to adjust themselves to the inner periphery of the drum, and means to free the shoes from the drum to enable the platen to be independently rotated.

3. In a typewriting machine, the combination with a line-space wheel having a drum provided with a smooth periphery, and a platen and platen axle rotatable relatively thereto, of a clutch mechanism to connect the line-space wheel and platen, including friction dogs in the form of levers each normally pressed against said smooth periphery of the drum at one end and pivoted at the other end, a head slidable along the platen axle, beveled teeth projecting from the head to engage the levers and release them from the line-space wheel, and a finger piece for sliding said head.

4. In a typewriting machine, the combination with a line-space wheel, a platen and its axle, said plate and axle rotatable relatively to said wheel, the latter having a smooth periphery, of a clutch mechanism to connect the platen and line-space mechanism including pivoted arms, the free ends of which have frictional wedging engagement with said smooth periphery of the line-space

wheel, a head slideable on the platen axle, teeth projecting from the head and having beveled ends engaging the arms to crowd them toward each other to disconnect the platen and line-space wheel, and a finger-piece through which the head is operated.

5. The combination with a platen and a line-space wheel, of a clutch connection therebetween comprising a drum and a pair 10 of pivoted levers, said levers being mounted to bear at their free ends against the inner periphery of the drum and having a length as great as practicable within the dimensions of the drum, for effecting an engagement 15 with the drum by a slight movement of said levers, resilient means to press the levers in opposite directions to connect the line-space wheel to the platen, and means to release said levers.

20. 6. The combination with a platen, its axle, and a line-space wheel, of a clutch connection therebetween comprising a drum and a pair of pivoted levers, said levers mounted to bear at their free ends against the inner 25 periphery of said drum in normal engagement therewith, the pivot of each lever being so placed that a line from said pivot to the working point of said lever is nearly 30 diametric of the drum, resilient means to press the levers in such opposing directions as to bind the line-space wheel to the platen, and means to release said levers; said 35 releasing means comprising a device mounted on said axle to slide along the same, and having at one end a finger-piece and at the other end beveled members to engage said levers near their free ends.

7. The combination with a platen and a line-space wheel, of connecting means there- 40 between comprising a drum, a member having an annular flange fitting in said drum to form a bearing therefor, and a pair of levers pivoted to the flanged member within said flange, the pivot of each lever being so 45 placed that a line from said pivot to the working point of said lever is nearly diametric of the drum, said flange cut away to permit the engagement of the levers with the drum, and resilient means to press the 50 levers in such directions as to bind the drum to said flanged member.

8. In a typewriting machine, the combi- 55 nation with a platen, a platen axle, and a line-space wheel, of a pair of dogs for connecting said platen to said line-space wheel, said dogs having a common pivot and extending on opposite sides of the platen axle, and a bow-spring between said dogs and ar- 60 ranged circumjacent said axle and expand- ing to force said dogs apart.

9. In a typewriting machine, the combi- 65 nation with a line-space wheel having a drum, and a platen rotatable relatively thereto, of a friction clutch mechanism in-

cluding a pair of wedging arms, each 65 pivoted at one end and extending trans- versely of the platen axis and at the other end having a shoe pivotally mounted thereon and normally frictionally engaging the inner periphery of the line-space wheel to 70 lock the drum and platen together, the pivot of each arm being so placed that a line from said pivot to the working point of said arm is nearly diametric of the drum, and means to shift said shoes out of contact with 75 the drum.

10. In a typewriting machine, the combi- 80 nation with a line-space wheel having a drum, and a platen rotatable relatively thereto, of a disk turning with the platen 85 and having an annular bearing flange thereon having a smooth periphery and a cut- away part; the line-space wheel and drum loosely mounted upon the disk and flange so that the latter may turn relatively thereto, 90 the exterior surface of said flange forming a bearing surface for the interior surface of said drum, wedging friction dogs in the form of levers pivoted to the disk and ex- 95 tends thereacross and projecting through said cut-away part, spring means for press- ing the free ends of the levers away from each other into wedging engagement with said interior periphery of the drum to fric- 100 tionally prevent relative movement between the platen and the line-space wheel in both directions; the pivot of each lever being so placed that a line from said pivot to the working point of said lever passes nearly through the axis of the drum, and means to release the levers.

11. The combination with a platen and a line-space wheel, of a clutch mechanism con- 105 necting them, comprising a drum and a pair of pivoted levers, said levers at their free ends mounted to bear normally against only the inner periphery of said drum, the pivot of each lever being so placed that a line from said pivot to the working point of said lever is disposed in a direction nearly radial 110 of the drum, to enable a self-wedging action to occur between the drum and lever, resili- ent means to press the levers in such oppos- 115 ing directions as to prevent relative move- ment between the line-space wheel and the platen in both directions, and means to re- lease said levers.

12. In a typewriting machine, the combi- 120 nation with a platen and its axle, of a wheel rotatably mounted on said axle, and a pair of pressure-releasable, pivoted, self-binding members normally clutching together the wheel and the platen and having their pivots arranged as far as practicable from their 125 working points within the dimensions of the wheel for effecting an engagement between said wheel and said platen by a slight move- ment of said members, said members acting

oppositely, to prevent relative movement of said wheel and said platen in both directions.

13. In a typewriting machine, the combination with a line-space wheel and a platen rotatable relatively thereto, of intermediate connecting and disconnecting mechanism, including a drum or ring and a pair of oppositely acting, self-binding levers, said drum and levers having unyielding opposed frictional surfaces, resilient means to force said levers in opposite directions into surface-binding contact with said drum or ring, and means to disengage said levers from said drum; said levers so mounted that relative movement of the platen and wheel in one direction tends to augment the binding effect of one of said levers, and relative movement of the platen and wheel in the opposite direction tends to augment the binding effect of the other of said levers.

14. The combination with a platen, and a line-space wheel rotatable relatively thereto, of a connection therebetween comprising a clutch member having a circular peripheral clutching surface, and a pair of opposed frictional clutching dogs, each pivoted at one end and at the other end engaging said surface, the pivot of each dog being so placed that the arc described by the clutching end of the dog, in moving about its pivot, converges toward the curve of said peripheral surface, but so nearly coincides with the curvature of said surface as to enable a relative rotation of said wheel and said platen to cause the dog to bite said surface and automatically bind itself thereto, to lock said wheel and platen together; and means to release said dogs.

15. The combination with a platen, and a line-space wheel rotatable relatively thereto, of a connection therebetween comprising a clutch member having a circular peripheral clutching surface, and a pair of opposed frictional clutching dogs, each engaging said surface at one end and at the other end being mounted on a common pivot with the other dog, said pivot so placed that the arc described by the clutching end of each dog, in moving about its pivot, converges toward the curve of said peripheral surface, but so nearly coincides with the curvature of said surface as to enable a relative rotation of said wheel and said platen to cause the dog to bite said surface and automatically bind itself thereto, to lock said wheel and platen together; and means to release said dogs.

16. The combination with a platen, and a line-space wheel rotatable relatively thereto, of a connection therebetween comprising a clutch member having a circular peripheral clutching surface, and a pair of opposed frictional clutching dogs, each pivoted at one end and at the other end engag-

ing said surface, the pivot of each dog being so placed that the arc described by the clutching end of the dog, in moving about its pivot, converges toward the curve of said peripheral surface, but so nearly coincides with the curvature of said surface as to enable a relative rotation of said wheel and said platen to cause the dog to bite said surface and automatically bind itself thereto, to lock said wheel and platen together; and means to release said dogs simultaneously.

17. The combination with a platen, and a line-space wheel rotatable relatively thereto, of a connection therebetween comprising a clutch member having a circular peripheral clutching surface, a frictional clutching dog pivoted at one end and at its other end engaging said surface, the pivot of said dog being so placed that the arc described by the clutching end of the dog, in moving about its pivot, converges toward the curve of said peripheral surface, but so nearly coincides with the curvature of said surface as to enable a relative rotation of said wheel and said platen in one direction to cause said dog to bite said surface and automatically bind itself thereto, to lock said wheel and platen together, and self-binding frictional clutching means automatically engaging said surface during relative rotation of said wheel and said platen in the opposite direction, to lock said wheel and platen together; and means to release said dog and said self-binding means.

18. The combination with a platen, and a line-space wheel rotatable relatively thereto, of a connection between said platen and said wheel including a clutch member having a circular peripheral clutching surface, and a frictional clutching dog pivoted at one end and at its other end engaging said surface, the pivot of said dog being so placed that the arc described by the clutching end of the dog, in moving about its pivot, converges toward the curve of said peripheral surface but so nearly coincides with the curvature of said surface as to enable a relative rotation of said wheel and said platen in one direction to cause said dog to bite said surface and automatically bind itself thereto, to lock said wheel and platen together; and means to release said dog.

19. The combination with a platen, and a line-space wheel rotatable relatively thereto, of a connection therebetween comprising a clutch member having a circular peripheral surface, and a pair of opposed frictional clutching dogs, each pivoted at one end and at the other end engaging said surface, the pivot of each dog being so placed that the arc described by the clutching end of the dog in moving about its pivot, converges toward the curve of said peripheral

surface, but so nearly coincides with the curvature of said surface as to enable a relative rotation of said wheel and said platen to cause the dog to bite said surface and 5 automatically bind itself thereto, to lock said wheel and platen together; resilient means interposed between said dogs to force

said clutching ends into such engagement, and means to release said dogs.
